US00D802332S

(12) **United States Design Patent** (10) **Patent No.:** **US D802,332 S**
(45) **Date of Patent:** **** Nov. 14, 2017**

(54) **POSITION STOP FOR A BLIND SYSTEM**

(71) Applicant: **Acmeda Pty Ltd**, Broadmeadows, VIC (AU)

(72) Inventors: **Dean John Jay**, Gladstone Park (AU); **Riccardo Santilli**, Reservoir (AU)

(73) Assignee: **Acmeda Pty Ltd**, Broadmeadows VIC (AU)

(**) Term: **15 Years**

(21) Appl. No.: **29/536,641**

(22) Filed: **Aug. 18, 2015**

(30) **Foreign Application Priority Data**

Feb. 19, 2015 (AU) 201510895

(51) **LOC (10) Cl.** **06-10**

(52) **U.S. Cl.**

USPC **D6/580**

(57) **CLAIM**

The ornamental design for a position stop for a blind system, as shown and described.

DESCRIPTION

FIG. 1 is a perspective view of the position stop for a blind system of the present invention;

FIG. 2 is a back view thereof;

FIG. 3 is a top view thereof;

FIG. 4 is a front view thereof;

FIG. 5 is a bottom view thereof;

FIG. 6 is a right side view thereof; and,

FIG. 7 is a left side view thereof.

The broken lines in the drawings depict features of the article that form no part of the claimed design.

1 Claim, 7 Drawing Sheets
